(57) **CLAIM**

The ornamental design for the solar firefly swaying lights, as shown and described.

DESCRIPTION

FIG. 1 is a perspective view of the solar firefly swaying lights showing my new design;

FIG. 2 is a front view thereof;

FIG. 3 is a back view thereof;

FIG. 4 is a left side view thereof;

FIG. 5 is a right side view thereof;

FIG. 6 is a top plan view thereof; and,

FIG. 7 is a bottom plan view thereof.

The broken lines shown on the drawings depict portions of the solar firefly swaying lights that form no part of the claimed design.
